J. H. KEARNS,
RAILWAY ROLLING STOCK,
APPLICATION FILED OCT. 11, 1913.

1,085,738.

Patented Feb. 3, 1914.

UNITED STATES PATENT OFFICE.

JAMES H. KEARNS, OF FRANCIS, OKLAHOMA.

RAILWAY ROLLING-STOCK.

1,085,738.

Specification of Letters Patent.

Patented Feb. 3, 1914.

Application filed October 11, 1913. Serial No. 794,712.

To all whom it may concern:

Be it known that I, JAMES H. KEARNS, a citizen of the United States, residing at Francis, in the county of Pontotoc and State of Oklahoma, have invented certain new and useful Improvements in Railway Rolling-Stock, of which the following is a specification, reference being had to the accompanying drawings.

10 This invention relates to certain new and useful improvements in railway rolling stock and has for its primary object to provide improved and novel means for supporting in upright position the apron carried by the locomotive and engaged with the tender when said locomotive and tender are coupled together.

Another object is to support the apron in such manner that should the locomotive and 20 tender become uncoupled, the apron will be automatically locked in horizontal position, thereby eliminating all danger of the train man standing upon the apron falling between the locomotive and tender.

25 A further object is to generally improve and simplify the construction and operation of the supporting means for the apron and the means for locking the said apron in horizontal position.

30 With the above and other objects in view, my invention consists in certain novel constructions, combinations, and arrangements of parts to be hereinafter more fully described, claimed, and illustrated in the accompanying drawings, in which,

Figure 1 is a side elevational view, partly in section, showing my device in use, portions of a locomotive and tender being shown in dotted lines; Fig. 2 is a view similar to 40 Fig. 1, showing the parts of my invention slightly enlarged and indicating the device in raised position, by dotted lines; Fig. 3 is a detail sectional view on the line 3—3 of Fig. 2; and Fig. 4 is a detail sectional view 45 on the line 4—4 of Fig. 2.

Referring more particularly to the drawings, 1 designates a portion of a locomotive having the apron 2 hinged thereto along one longitudinal edge of said apron, while the opposite edge of said apron normally rests upon the sill of the tender 3 when the locomotive and tender are coupled together.

Secured to the under face of the apron 2 are the depending perforated ears 4 to which are pivoted the upper ends of the reciprocating rods 5 by means of the pivot

pins 6 engaged through said perforated ears 4 and the flattened upper ends of the rods 5. The rods 5 are slidably engaged in the upper cylindrical portions of the guide members 7 while the lower portions of said members 7 are flattened and pivoted to the out-turned ends 8 of the rock shaft 9, by the pivot pins 10. The rock shaft 9 also has a depending offset central portion, the purpose of which will presently appear.

When the rock shaft 9 is in normal position, the out-turned ends 8 thereof are in a substantially horizontal position, thereby supporting the guide members 7 in their lowermost positions and allowing the free longitudinal edge of the apron 2 to assume a position below the plane of the hinged longitudinal edge of said apron, before the shoulders 5' of the reciprocating rods 5 engage against the upper ends of the guide members 7 and thereby prevent further downward movement of the free longitudinal edge of the apron 2.

Should the locomotive and tender become uncoupled while in motion, the U-shaped member 11 secured to the tender and engaged around the depending central offset portion 9' of the rock shaft 9 will cause said shaft 9 to rotate until the depending central offset portion 9' thereof is in horizontal position, owing to the fact that as the locomotive moves away from the tender, the depending offset central portion 9' of the shaft 9 will be drawn against the central portion 90 of the U-shaped member 11 and will be compelled to assume a horizontal position before freeing itself from said U-shaped member 11. After the rock shaft 9 has been forced to rotate in this direction, downward movement of the free longitudinal edge of the apron 2 is prevented, owing to the fact that the lower ends of the guide members 7 are forced against the face of the locomotive and the lower flat portions of said guide members 7 are in a substantially vertical position while the upper cylindrical portions thereof are inclined outwardly.

It will be understood that while the locomotive and the tender are in motion, the 105 apron 2 will be free to raise and lower when said engine and tender are passing over uneven portions of the track or over the rail joints, owing to the fact that the reciprocating rods 5 are free to reciprocate within the 110 cylindrical upper portions of the guide members 7.

From the foregoing it will be clearly apparent that I have provided improved and novel means for supporting the apron employed covering the space between a locomotive and tender or between two cars, and it will further be apparent that should the locomotive and tender or cars between which the apron is positioned be accidentally uncoupled, the apron will be automatically raised to a substantially horizontal position and locked in said position, thereby eliminating all danger of one longitudinal edge of the apron falling down and allowing the train man standing on the apron to drop between the cars. It will also be clearly apparent that this device may be readily and cheaply applied to locomotives and tenders or cars now in general use without altering the construction of the same and will be highly efficient and effective in use.

While I have shown the preferred embodiment of my device, it will be clearly apparent that minor changes in the details of construction and arrangement of parts may be made within the scope of the appended claims without departing from the spirit of my invention or sacrificing any of the advantages of the same.

What I claim is:—

- 30 1. The combination with a locomotive and tender, of an apron carried by the locomotive and adapted to rest upon the tender, means for limiting downward movement of the apron, and means for raising the apron and locking the same in horizontal position upon uncoupling of the locomotive and tender.
- 35 2. A device of the class described comprising the combination with a locomotive and tender, of an apron having one longitudinal edge hinged to the locomotive while

its opposite longitudinal edge normally rests upon the tender, means for limiting downward movement of the last mentioned longitudinal edge of the apron, and means for raising the last mentioned longitudinal edge 45 of the apron and locking the same in raised position upon uncoupling of the locomotive and tender.

3. A device of the class described comprising the combination with a locomotive 50 and tender, of an apron hinged to the locomotive and engaged upon the tender, a rock shaft having a depending portion and out-turned portions, guide members secured to the out-turned portions of the rock shaft, 55 said guide members having outwardly inclined cylindrical portions, rods secured to the under face of the apron and slidably engaged in the cylindrical portions of the guide members, said rods having shoulders 60 for engagement against the upper ends of the cylindrical portions of the guide members to limit downward movement of the apron, means for mounting the rock shaft upon the locomotive, and means carried by 65 the tender for engagement with the depending portion of the rock shaft to compel said depending portion to assume a horizontal position and thereby cause rocking movement of the rock shaft upon uncoupling of the locomotive from the tender, whereby the apron will be slightly raised above its normal position and locked in said raised position.

In testimony whereof I hereunto affix my 75 signature in the presence of two witnesses.

JAMES H. KEARNS.
